UNITED STATES PATENT OFFICE.

EDWARD E. LARSON, OF THOMPSON, IOWA.

TRACTOR.

1,352,286.

Specification of Letters Patent. Patented Sept. 7, 1920.

Application filed March 9, 1918, Serial No. 221,490. Renewed April 30, 1920. Serial No. 378,015.

To all whom it may concern:

Be it known that I, EDWARD E. LARSON, a citizen of the United States, residing at Thompson, in the county of Winnebago and State of Iowa, have invented a new and Improved Tractor, of which the following is a full, clear, and exact description.

My invention relates to tractors and an object thereof is to provide a simple and efficient tractor characterized by propelling members of the walking type.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a vertical section through a tractor frame on line 1—1, Fig. 2, the main parts of the tractor being shown in elevation;

Fig. 2 is a plan of the tractor;

Fig. 3 is a section on line 3—3, Fig. 2;

Fig. 4 is a section on line 4—4, Fig. 1;

Fig. 5 is a section on line 5—5, Fig. 3;

Fig. 6 is an elevation of a shoe-carrying pinion; and

Fig. 7 is a fragmentary elevation of the chain from which the shoe is suspended.

Referring to the drawings, 8 is a rigid frame having in front an axle 9 which carries a pair of wheels 10 operable by a steering mechanism 11 a fragment only of which is shown in the drawings. In the rear the frame carries a pair of shoes 12, the shoes being disposed on the opposite sides of the central longitudinal plane of the frame. Each of the shoes is suspended from a corresponding carriage 13 mounted to roll on corresponding tracks 14 carried by the frame. Each of the carriages 13 is constrained to travel with the links of a corresponding endless chain 15, the chains engaging corresponding sprockets 16 and 17 revolvably mounted in suitable bearings provided on the frame 8.

Each of the sprockets 16 is provided with a corresponding planetary differential 18, both differentials being driven from a motor 19 through the medium of an endless chain 20 coupling the motor 19 to a sprocket 22, which sprocket is constrained to revolve with

the pinions of the two differentials. Each of the differentials is coupled by an endless chain 23 to a corresponding sprocket 24. Each sprocket is constrained to revolve with a corresponding shaft 25. The two shafts are suspended from the frame independently of one another and each carries a pinion 26 in mesh with a corresponding rack 27 carried by a beam 28 extending from the shoe 12 alining with the corresponding pinion 26, the beam being rigidly connected to the shoe. To facilitate the movement of the beam by the shaft 25 the same is provided with rollers 29 which form roller bearings for the portion of the beam 28 which is below the rack.

As the motor 19 rotates the sprockets 16 in the direction indicated by the arrows, a track 14 is caused to travel on a carriage 13, whereby the frame 8 is caused to move in the direction indicated by the arrow in Fig. 1. The movement of the tracks on the carriages imparts a rotary movement to the shafts 25 through the medium of the racks 27, and when the shafts 25 are rotated in the same direction as the sprockets 16 the speeds of said sprockets 16 are greater than if the shafts 25 were rotated in the opposite direction. When the shafts 25 rotate in the direction opposite to the sprocket 16 the housing of the differentials will also rotate in the opposite direction to the sprockets 16. The gearing of the differentials decreases the speed of the sprockets 16 when the differential housings rotate in a direction opposite to the sprockets, consequently the speed of the chain 10 will be greater when the carriage is on the upper part of the tracks 14. The differential mechanism, therefore, carries the shoe not under load at a greater speed than the frame moves on the carriage; and it will be seen that the speed must be slightly more than that of the frame, so that a shoe moving from the inoperative to the operative position will be in time to engage the lower face of the track before the shoe that is at the end of its operative position begins to roll off the lower face of the track.

To properly support the load while the carriage 13 is turning the track 14, the sprockets 16 and 17 are provided with brackets 30 for engaging and supporting the carriage while it turns with the sprockets.

From the above description it will be seen

that the shoes 12 may be considered as supports on which the frame travels. The shoes are like walking means which are successively placed into operative position so that the frame can slide thereon, the differential serving to move a support quickly during its inoperative position to bring it in time into operative position with reference to the frame to support the frame as the frame begins to leave the other support, that is, as the other support is rendered inoperative. It is self-evident that the form of the shoes may be varied according to the ground in which the tractor is to be used.

15 While I have described the principle of operation, together with the device which I now consider to be the best embodiment thereof, I desire to have it understood that the device shown is merely illustrative and 20 that such changes may be made as are within the scope of the appended claims.

I claim:

1. A tractor comprising a frame, rolling means supporting one end of the frame, a 25 pair of endless tracks associated with the other end of the frame, a carriage on each of the tracks, means for moving the carriages and the tracks relative to one another, a shoe associated with each of the 30 carriages, and means associated with the shoe for accelerating the movement of the carriage when the shoe is moved from the inoperative into the operative position.
2. A tractor comprising a frame, rolling 35 means supporting one end of the frame, supports for the other end of the frame, tracks for said supports, means for moving the tracks and supports relative to one another whereby the frame is moved on the 40 supports, and means for moving the supports on the tracks at a greater speed than the frame moves, whereby a support can be moved quicker from the inoperative to the operative position than from the operative to the inoperative position.
3. A tractor comprising a frame, rolling 45 means supporting one end of the frame, supports for the other end of the frame, a roller bearing interposed between the supports and the frame, endless tracks for said rolling means of the supports, means for moving said frame and supports relative to one another, and means associated with said moving means for increasing the relative speeds of said frame and supports when said supports and frame are moved in the same direction.
4. A tractor comprising a frame, rolling

means supporting one end of the frame, supports for the other end of the frame, means 60 for moving said supports and frame relative to one another in the same and opposite directions, and means for increasing the speed of said supports when said supports are moving in the same direction as the 65 frame when compared with the speed of the supports when moving in a direction opposite to that of the frame.

5. A tractor comprising a frame, rolling 70 means supporting one end of the frame, 75 shoes for the other end of the frame, a carriage associated with each shoe, an endless track on the frame for each of the carriages, an endless chain mounted to revolve about each track and connected to the carriage on the track, means for imparting rotary motion to the endless chains, differentials interposed between the endless chains and the motion-imparting means, and means for revolving the differential housings operable 80 by the shoes.

6. A tractor comprising a frame, wheels 85 supporting the front of the frame, shoes for the rear of the frame, a carriage associated with each shoe, an endless track for 90 each of the carriages, an endless chain mounted to travel about each of the tracks and connected to the carriage on the track, a differential associated with each of the endless chains, means for actuating the chains through the differentials, revolute means at the front of the frame, motion-transmission means from the revolute means at the front to the differentials, and means from the shoes to the revolute means 95 for operating the said revolute means.

7. A tractor comprising a frame, wheels 100 supporting the front of the frame, shoes for the rear of the frame, a carriage associated with each shoe, an endless track for each 105 of the carriages, an endless chain revolutely mounted about the track and connected to the carriage on the track so that the carriage is constrained to move with the chain, a differential associated with each chain, means for actuating the chains through the differentials, a rack associated with each of the 110 shoes, a pinion for each rack, a shaft for each pinion constrained to rotate therewith, and motion-transmission means from each of the shafts to the differential associated with the chain constrained to move with the carriage the rack of which actuates the shaft.

EDWARD E. LARSON.
